[57] CLAIM

The ornamental design for a reagent bottle for a clinical laboratory analyzer, as shown and described.

DESCRIPTION

FIG. 1 is a side elevational view of a reagent bottle for a clinical laboratory analyzer showing my new design, with all other sides being identical to that shown;

FIG. 2 is a top plan view thereof;

FIG. 3 is a bottom plan view thereof;

FIG. 4 is a partial cross-sectional view thereof taken along the line IV—IV of FIG. 2; and,

FIG. 5 is a cross-sectional view thereof taken along the line V—V of FIG. 3.
